WITNESSES.

John Graham

UNITED STATES PATENT OFFICE.

JOHN GRAHAM, OF CHICAGO, ILLINOIS, ASSIGNOR TO MARDER, LUSE & CO., OF SAME PLACE.

DESIGN FOR A FONT OF PRINTING-TYPE.

SPECIFICATION forming part of Design No. 14,667, dated February 12, 1884.

Application filed October 12, 1883. Term of patent 14 years.

To all whom it may concern:

Be it known that I, JOHN GRAHAM, a citizen of the United States of America, residing at Chicago, in the county of Cook and State 5 of Illinois, have invented and produced a new and original Design for a Font of Printing-Type, of which the following is a specification, reference being had therein to the accompanying copies of the design.

10 My invention consists of a new design for a font of printing-type of script letters, formed and shaded as hereinafter described, and as shown in the accompanying printed specimens of the font.

15 The capital letters, except D, O, Q, U, W, and X, are ornamented with a straight dash, having a heavy terminal and a slope of about twenty-five degrees from the perpendicular. The capital letter D has a heavy terminal dash 20 on the same slope of the letter. The capital letters O and Q begin with a heavy bulb, followed by a heavy curve to the left, and the characteristic of the capital letter Q is a heavy terminal dash on a slope of about forty-five 25 degrees from the perpendicular, connected by a light loop with the preceding curve. The capital letters U, W, and X begin with a heavy dash on the same slope of the letters.

The small letters a, e, f, g, j, k, p, q, y, and z have for a connecting-line a straight dash, with 30 a heavy terminal and a slope of about twenty-five degrees from a perpendicular. The finishing parts of the small letters h, m, n, and r are connected with the preceding stroke by a light line beginning at the left of the same. 35 The small letter e has a light connecting-line, followed by a light curve occupying the upper half of the letter, and terminating with a heavy stroke. The small letter t is light at the top and crossed by a straight dash, with a 40 heavy terminal and a slope of about twenty-five degrees from a perpendicular.

What I claim as new, and desire to secure by Letters Patent, is—

45 The new design for a font of printing-type of script letters, formed and shaded as described, and as shown in the printed specimens.

In testimony whereof I affix my signature in presence of two witnesses.

JOHN GRAHAM.
